United States Patent Office.

WILLIAM CORSON, OF CAMDEN, OHIO.

Letters Patent No. 78,789, dated June 9, 1868.

IMPROVEMENT IN PORTABLE FENCES.

The Schedule referred to in these Letters Patent and making part of the same.

TO ALL WHOM IT MAY CONCERN:

Be it known that I, WILLIAM CORSON, of Camden, in the county of Preble, and State of Ohio, have invented a new and improved Portable Fence; and I do hereby declare that the following is a full and exact description of the same, reference being had to the accompanying drawings, and to the letters of reference marked thereon.

This invention consists in a method of fastening together firmly the panels of portable fences by a simple construction and arrangement of the bars, as will be hereinafter fully described.

In the drawings, A and B, fig. 1, represent the panels when ready to be united, constructed as shown, of the same general shape and dimensions, and of any desired number of bars and length. $a a' b b'$ represent cross-pieces for the purpose of fastening the bars together to form the panel. $a' a' b' b'$ represent projections of the bars, by which the panels are united across the ends of the former, of which $a' a'$ passes the bar a'' , for the purpose of forming sockets for the reception of the latter, $b' b'$. The two upper bars of the panel A are cut away upon their lower side, and the two lower ones upon their upper side, corresponding with which the projections b' are also cut away in such manner that the one fits snugly into the other.

The centre-bars of the panels are somewhat differently constructed. d represents a notch, cut in the upper side of the bar D, and c represents the corresponding part cut away in the bar C, the former of which is made of flexible material, and fastened only at the point d' .

When it is desired to unite the panels, the bar D is depressed, and the projections b' passed into the sockets of the panel A until the notch d is reached, when the bar D, being freed, it immediately resumes its natural position, and, shutting down into the notch, completes the fastening. By this arrangement the panels are easily and firmly united.

Having thus described my invention, what I claim as new, and desire to secure by Letters Patent, is—

The flexible bar D, in combination with bar C and notch c , substantially as described.

WILLIAM CORSON.
